US0D1082602S

(12) **United States Design Patent** (10) **Patent No.:** **US D1,082,602 S**
(45) **Date of Patent:** **** Jul. 8, 2025**

(54) **PLANT CLIMBING POLE**

(71) Applicant: **Xiangshui Yuchen Horticultural Products Co., Ltd.**, Yancheng (CN)

(72) Inventor: **Hongjie Zhang**, Jiangyin (CN)

(73) Assignee: **Xiangshui Yuchen Horticultural Products Co., Ltd.**, Yancheng (CN)

(**) Term: **15 Years**

(21) Appl. No.: **29/981,601**

(22) Filed: **Dec. 31, 2024**

(51) **LOC (15) Cl.** **11-02**

(52) **U.S. Cl.**

USPC **D11/143**; D11/149; D8/1

(58) **Field of Classification Search**
